WILLIAM F. HENDRY, OF OSSINING, NEW YORK, ASSIGNOR TO E. D. ANDERSON, INC.,
OF NEW YORK, N. Y., A CORPORATION OF DELAWARE

METHOD AND MEANS FOR WRAPPING PACKAGES

Application filed January 4, 1929. Serial No. 330,357.

This invention relates to methods and means for wrapping packages.

It is an object of my invention to provide a method and means for wrapping packages with sheets of material, the dimensions of which vary with a change in humidity of the surrounding atmosphere.

Other objects and advantages will be made clear hereinafter.

10 It has been found that it is impractical, if not impossible, to wrap packages with an ordinary wrapping machine where the humidity of the atmosphere in which the machine works varies appreciably, and hygroscopically variable wrapping material is used. It has been found that certain hygroscopic wrapping materials, for example, Cellophane, vary greatly in dimensions with changes in the humidity of the atmosphere in which they are placed.

20 While it might be possible for a standard packing machine to operate with glassine or other such hygroscopic wrapping material, provided the humidity of the surrounding atmosphere be maintained fairly constant, no

25 perfectly reliable and satisfactory method has as yet been devised, satisfactorily to wrap packages by machinery with such material.

Most machines are adapted to wrap a package very tightly so as to give it a smooth appear-

30 ance. If such a machine wraps a package with Cellophane on a damp day it is very possible that the covering of the package may split when the humidity of the atmosphere is lowered sufficiently by removal of the package.

35 to some drier place or by a change in weather conditions. The reason for this is that the covering on a package will shrink and the tension therein may be increased sufficiently to tear the wrapper. This would be espe-

40 cially true with packages having sharp corners. On the other hand if the wrapping operation were performed on a very dry day the package when wrapped would have a smooth appearance, but upon a change in

45 weather carrying with it an increase in humidity of the atmosphere the wrapping of the package will loosen and present an untidy appearance.

50 In accordance with my invention I propose to form a wrapper of Cellophane or similar

hygroscopically expandable material by folding a sheet of it about a pattern having the desired shape, and slightly larger dimensions than the package to be enclosed, this forming process being carried out in an atmosphere 53 of relatively high humidity, preferably higher than that of any atmosphere in which the package will be placed at a later time. After the wrapper has been folded into its desired shape it is removed from the pattern and 60 slipped over the package which is to be covered, and thereafter sealed by folding it and fastening the end portions thereof. If desirable the pattern upon which the wrapper is initially folded may be made hollow with 65 thin sides so that after the wrapper has been given its desired shape the package which is to be enclosed may be slipped within the hollow form and then both the package and wrapper withdrawn from the form at the 70 same time. By this process the wrapper is properly positioned on the package in a perfectly smooth condition with a minimum of effort.

After the completely wrapped package is 75 removed from the room wherein the enclosing process has been carried out it is exposed to the ordinary atmosphere which is of a normal humidity below that of the room wherein the wrapper was applied. This exposure 80 shrinks the wrapper smoothly on the package without subjecting it to excessive strains, thereby producing a neat and well appearing article. By properly gauging the size of the pattern and the humidity of the wrapping 85 room with relation to the average humidity of the locality in which the packages are to be placed on display and sold, it is possible to cause the wrapper to contract tightly around the package so as to present a smooth appear- 90 ance, without damaging the wrapper. If desirable the finished articles may be freed from the moisture absorbed during wrapping by placing them in a drying room upon comple- 95 tion of the wrapping operation.

If the material forming the wrapper shrinks instead of expands with an increase in per cent humidity, the reverse process may be used. The wrapping process should then be carried out in a very low humidity atmos- 100

phere so that the wrapper may later shrink to the correct size.

Referring to the drawings, Fig. 1 shows a pattern for shaping the wrapper, with a sheet of material partly in place.

Fig. 2 shows a wrapper completely folded on the pattern.

Fig. 3 shows a wrapper being slipped from the pattern on to a package.

10 Fig. 4 shows a wrapper completely removed from the pattern and positioned on the package.

Fig. 5 shows the completed article.

15 Fig. 6 illustrates another method of wrapping wherein the package is being slipped inside of a hollow pattern having a wrapper thereon.

Fig. 7 shows the package and wrapper being removed from the pattern.

20 Referring more particularly to the drawings, reference numeral 1 indicates a pattern or die adjacent to which is placed a sheet of material 2, such as Cellophane. The pattern may be made solid, as shown, or may be made 25 hollow and collapsible so as to permit easy removal of the formed wrapper. The sheet 2 is wrapped around the pattern 1 by hand or in any other manner, occupying a position when finished, as shown in Fig. 2. One or 30 several convolutions of the sheet material 35 may be used as desired. After the sheet wrapper has been shaped to the form shown in Fig. 2 it is removed from the pattern 1 and placed on the package 5. This may be done by slipping the wrapper from the pattern and then placing the package therein in any desired manner. Preferably it is done by placing the package at the end of the pattern and slipping the wrapper directly on to the package, 40 thereby preventing wrinkling of the sheet material in handling. In order to facilitate removal of the wrapper the pattern may be made slightly tapered, if necessary. After the package has been enclosed as shown in 45 Fig. 4, the ends of the wrapper are tucked in, as shown in Fig. 5, and held in any suitable manner, for example, by pasting or by placing a seal 6 over the folds thereof.

50 As an alternative method which may be found more desirable in enclosing articles which are of slightly irregular shape the article may be thrust inside of a hollow pattern after the sheet of material has been folded therearound.

55 In Fig. 6 an article is shown partly inserted within a die having thin walls 3 and cut out portion 4 in the top and bottom faces thereof. The package and wrapper may be removed together from the pattern by gripping the 60 two at the openings 4 in the pattern. Thereafter, the package may be completed in the manner described in connection with Figs. 4 and 5. The advantage of this procedure is that the stiff walls of the pattern serve to 65 guide the sides of the package within the

wrapper without injuring the latter. Where this process is used the thickness of the side walls of the pattern should be properly proportioned with respect to the size of the article and the humidity of the wrapping atmosphere so that when the finished article is exposed to the ordinary atmosphere the wrapper will shrink onto the enclosed article so as to present a smooth appearance. Likewise, in connection with the method shown in Figs. 75 1 to 3, the size of the pattern or form should be so proportioned with respect to the article being wrapped that the desired shrinking effect will be obtained.

80 While I have described my process as carried out by hand, it will be obvious that it may be performed by suitable machinery as well. A specific modification has been described to illustrate the invention, but it is to be understood that various modifications and adaptations occurring to one skilled in the art may be made without departing from the spirit of the invention as expressed in the claims.

90 What I claim is:

1. The method of packaging which comprises folding a sheet of material around a pattern to form an open end wrapper, placing an article beside the pattern at an open end of the wrapper and moving the wrapper 95 from the pattern directly onto the article.

2. The method of packing which comprises forming around a pattern an expanded wrapper open at both ends, placing an article beside the pattern at an open end of the 100 wrapper, moving the wrapper from the pattern directly on to the article and thereafter shrinking the wrapper.

3. The method of packaging which comprises forming around a pattern in an atmosphere of high humidity, a wrapper of hygroscopically expansive material, open at both ends, placing an article beside the pattern at an open end of the wrapper, moving the wrapper from the pattern directly onto the 105 article and thereafter subjecting the wrapper to an atmosphere of lower humidity.

110 In testimony whereof, I have signed my name to this specification, this 31 day of December, 1928.

115 WILLIAM F. HENDRY.
